CLAIM

The ornamental design for a U-shaped sponge mop, as shown and described.

DESCRIPTION

FIG. 1 is a front elevational view of a U-shaped sponge mop embodying our invention;

FIG. 2 is a top plan view of the U-shaped sponge mop of FIG. 1;

FIG. 3 is a side elevational view of the U-shaped sponge mop of FIG. 1, the opposite side being a mirror image;

FIG. 4 is a side elevational view of the U-shaped sponge mop of FIG. 1, the mop being shown in a compressed, draining position with the sponge head removed for clarity of illustration, the opposite side being a mirror image; and,

FIG. 5 is a front elevational view of the U-shaped sponge mop of FIG. 4, the mop being shown in a compressed, draining position with the sponge removed for clarity of illustration.

The handle is shown broken away in the figures for convenience of illustration.
